(57) **CLAIM**

The ornamental design for a dashboard of a construction vehicle, as shown and described.

DESCRIPTION

FIG. 1 is a perspective view of a dashboard of a construction vehicle showing our new design; and, FIG. 2 is a front view thereof.

The broken lines in FIGS. 1 and 2, showing the outlying areas of the dashboard and numeric data are for illustrative purposes only and form no part of the claimed design.

1 Claim, 2 Drawing Sheets

FIG. 2
